DESIGN FOR A TEXTILE FABRIC OR SIMILAR ARTICLE

Harry A. Brown, Brooklyn, N. Y.

Application May 5, 1936, Serial No. 62,473

Term of patent 3½ years

To all whom it may concern:

Be it known that I, Harry A. Brown, a citizen of the United States, residing in the Borough of Brooklyn, county of Kings, city of New York, and State of New York, have invented a new, original, and ornamental Design for a Textile Fabric or Similar Article of which the following is a specification, reference being had to the accompanying drawing, forming a part thereof.

The figure is a plan view of a textile fabric or similar article showing my new design.

The main features of the design consist of a series of two parallel transverse stripes of heavy fancy yarn of different color woven into a fancy weave background, the stripes being slightly raised above the surface of the fabric.

I claim:

The ornamental design for a textile fabric or similar article as shown and described.

In testimony whereof I have signed this specification.

HARRY A. BROWN.
